UNITED STATES PATENT OFFICE.

GEORGE R. McDERMOTT, OF CHICAGO, ILLINOIS.

AUTOMATIC GOVERNOR FOR GAS PRODUCERS.

Application filed September 1, 1920. Serial No. 407,491.

To all whom it may concern:

Be it known that I, GEORGE R. McDERMOTT, a citizen of the United States, residing at Chicago, in the county of Cook and State 5 of Illinois, have invented certain new and useful Improvements in an Automatic Governor for Gas Producers, of which the following is a specification.

My invention relates to an automatic governor for gas producers and has for its primary object the provision of an automatic governor which will control the volume of air to a gas producer without attention on the part of an operator or workman. 10 Another object of my invention is the provision of an apparatus which will maintain a constant volume of air supply to a gas producer rather than a constant pressure to said producer because the pressure will vary 15 in the operation of the gas producer.

In the operation of gas producers, as the gas main and producer become dirty, the back pressure of the air forced through the gas producer becomes greater and the volume of air supplied to the gas producer thereby decreases, thus decreasing the quantity of gas produced by the gas producer. It is not possible in the operation of gas producers to have each one watched at all times 20 and control by hand the admission of steam to the prime mover so that the supply of air is increased as the back pressure increases, or diminished as the back pressure decreases due to the variation in the flow of the air 25 through the producer or for some other cause, which causes an increase in the air delivery of the blower above the desired quantity.

My improved device is entirely automatic 40 in its action and as the back pressure increases the apparatus is controlled so that an added volume of air is forced into the producer; or, as the back pressure decreases, thus causing the blower to deliver too great 45 a quantity of air to the producer, the apparatus is also controlled, so that a constant supply of air is maintained, thus keeping up the constant rate of gas production on the part of each producer.

These and other objects of my invention 50 will be more fully and better understood by reference to the accompanying sheet of drawings, in which—

Figure 1 is a vertical view partially in 55 elevation and partially in section of my improved device;

Figure 2 is a view in elevation of the compound levers used to control the admission of steam; and,

Figure 3 is a view in elevation of a steam 60 driven blower for supplying air to the producer.

Referring now specifically to the drawings, a section of the foundation 10 upon which a gas producer is mounted is shown 65 having a blast pipe 11 extending therethrough to which an elbow 12 is connected in any suitable manner and to which a vertically extending blast pipe 13 is connected, the pipe 13 having an integral annular flange 14 at its upper end. A steam turbine driven blower 15 is provided having an outlet pipe 16 having an annular flange 17, bolts 18 extending through the flanges 17, the exhaust pipe 16 and the flange 14 of the 70 blast pipe 13 so as to securely hold these members together. Located between the flanges 14 and 17 and held in position by the bolts 18 is a gasket 19 having an orifice 20 centrally located thereof, the orifice 80 20 being smaller in diameter than the outlet 16, also the blast pipe 13 leading to the gas producer. A turbine 21 is provided for driving the blower 15 which is supplied with steam through a pipe 22, a strainer 23 being provided in the steam blower to prevent foreign particles entering the turbine 21. Secured to the turbine 21 is a pair of legs 24 and 25, upon which is mounted a gasometer 26 composed of a bottom member 27 and a 90 top plate 28 having cylindrical side walls 29. Extending vertically through the gasometer 26 and through the top cover 28 thereof is a rod 30 which is attached to a guide member 30^a which in turn is secured to a bell 31 95 located inside of said gasometer and of slightly smaller diameter than the gasometer 26. A guide rod 30^b is secured to a plate member 32 seated in the bottom of the gasometer 26, and extends into the lower end 100 of the guide member 30^a so the bell 31 is movable in a vertical direction. The gasometer 26 is approximately filled with water 33 or any other fluid and has a chamber 34 in the upper portion thereof, the bell 31 being almost wholly submerged in the water 33 or other liquid in the gasometer. A pipe 35 is provided which extends through the side wall 29 of the gasometer and thence upward into the bell and terminates a short 110 distance short of the upper part of the bell 31. The said pipe 35 extends downwardly

and is connected to the outlet pipe 16 from the blower through an opening 36. A second pipe 37 is provided which is connected to the blast pipe 13 at 38, the two pipes 35 and 5 37 being connected to the blast supply pipe on each side of the orifice 20 in the gasket 19. The pipe 37 is secured to the wall 29 of the gasometer near its upper portion and leads into the upper part of the chamber 10 34 of the gasometer. Secured to the cover plate 28 is a valve base 39 upon which a valve is mounted and to which the steam supply pipe 22 is connected. The valve 40 has a valve cap 41 secured thereto with the 15 usual gland 42 surrounding a valve stem 43. The valve cap 41 has a vertically extending lever 44 secured thereto by means of a rivet or bolt 45, the link or member 44 having a lever 46 fulcrumed thereon at its upper 20 end, the lever 46 also being connected to the valve stem 43 by means of a link 47 and a rivet 48. Secured to said valve cap 41 is a member 49 slotted at its upper end and through which the lever 46 extends, the member 25 49 having a pin 50 extending therethrough so that the lever 46 is prevented from pulling the valve stem 43 out too great a distance, as hereinafter described.

Mounted upon said cover 28 is a fulcrum 30 member 51 through which a second lever 52 extends, the lever 52 being connected to the upper end of the rod 30 extending downwardly into the gasometer 26. A counterweight 53 is secured to the outer end of the 35 lever 52 and exerts its force upward upon the rod 30. Connecting the lever 46 and the lever 52 is a turnbuckle 54 which is secured to the lever 52 by means of a rivet 55 and to the lever 46 by means of a rivet 56.

40 A counterweight 57 is adjustably secured to the outer end of the lever 46 which can be adjusted to different points upon the end of the lever 46. A steam exhaust pipe 58 is provided leading from the turbine 21 45 to a T 59 and into a pipe 60 which is connected to the blast pipe 13, a valve 61 being provided so that the supply of exhaust steam can be turned off at any time if desired. A by-pass pipe 62 is connected to 50 the elbow 59 and leads to a valve 63 which in turn is connected to a pipe 64 which is connected to the steam supply pipe 22, so that if it is desired high pressure steam can be admitted around the turbine and into 55 the blast pipe 13 at any time.

In the operation of the device it will be understood that steam is admitted through the valve 40 into the supply pipe 22 and into the turbine 21 which starts an air blast 60 through the outlet pipe 16 and through the orifice 20 of the gasket 19 into the blast supply pipe 13. The orifice 20 being very much smaller than the outlet pipe 16 of the blower, there will be considerable back pressure developed just at this point which will 65 be communicated through the pipe 35 which terminates just underneath the upper edge of the bell 31 of the gasometer, thus tending to push the gasometer bell together with the rod 30 upward. Beyond the orifice 20 70 the air will exert a slightly less pressure than at the outlet 16 of the blower, the air passing through the pipe 37 and into the upper portion 34 of the gasometer 26; the lever 46 will thereupon be adjusted to admit 75 a predetermined supply or volume of air to the blast pipe 13, and, having been adjusted, any differential in the pressure at the points 36 and 38 on each side of the orifice 20 will be registered through the movement of the 80 gasometer bell 31 up or down, as the case may be, in the gasometer 26 which will, through the action of the levers 52 and 46, if the back pressure at the points 38 becomes greater, open the valve 40, thus admitting 85 a greater amount of steam into the turbine which will thus be driven at a higher rate of speed and resulting in an increased volume of air being supplied to the blast pipe 13; the supply of steam admitted to the turbine 90 being therefore controlled by the differential in the pressures developed upon each side of the orifice 20 so that when the volume of air supplied to the gas producer is determined this volume is automatically continued, because any increase in the back pressure will result in more steam being admitted to the turbine with the result that the turbine is driven faster and a greater supply of air driven into the blast pipe. 95

It will also be understood that while I have illustrated and described this device as applied to a gas producer, it can be used upon any operation where a given volume of gas is required to be supplied in any operation. 100

105 While I have described more or less precisely the details of construction of my invention, I do not wish to be understood as limiting myself thereto, as I contemplate 110 changes in form and the proportion of parts and the substitution of equivalents as circumstances may suggest or render expedient, without departing from the spirit or scope of my invention. 115

I claim:

1. In combination, a blower, steam actuating means for driving said blower, a blast conveying pipe leading from said blower, one portion of the passage through said pipe 120 being restricted, a gasometer having a floating bell therein, a valve connected to said floating bell and controlling said steam actuating means, a pipe connected to said gasometer above said bell, and a second pipe 125 connected to said gasometer below the bell, the said pipes being connected to the said blast conveying pipe to each side of the said restricted portion.
2. In combination, a blower, a steam tur- 130

- bine connected to said blower, a blast conveying pipe leading from said blower having a passage therethrough, one portion of which is restricted, a gasometer having a 5 floating bell therein, pipes connected to said blast conveying pipe on each side of said restricted portion and terminating in said gasometer above and below the said bell and beams connecting the said bell with a 10 valve for controlling the admission of steam to the said turbine.
3. In combination, a blower actuating means for driving said blower, a blast conveying pipe leading from said blower, a 15 plate in said blast conveying pipe having an opening therein of less diameter than the said blast conveying pipe, a gasometer having a floating bell therein, a valve connected to said floating bell and controlling said blower actuating means, a pipe connected 20 to said gasometer above said bell, and a second pipe connected to said gasometer below the bell, the said pipes being connected to the said blast conveying pipe on each side of said plate having a restricted opening 25 therein.
- Signed at Chicago, Illinois, this 11th day of August, 1920.

GEORGE R. McDERMOTT.
